UNITED STATES PATENT OFFICE.

LOUISE F. DION, OF NEW YORK, N. Y.

HOSE SUPPORTER.

Application filed December 10, 1921. Serial No. 521,331.

To all whom it may concern:

Be it known that I, LOUISE F. DION, a citizen of the United States, and a resident of New York, in the county of New York and State of New York, have invented certain new and useful Improvements in Hose Supporters, of which the following is a full, clear, and exact description.

My invention relates to hose supporters and has for its object to provide improved means for attaching the supporter to the hose in such manner that the same will not fall loose therefrom.

Another object of the invention is the provision of novel means for attaching the supporter to the hose whereby the hose is not damaged by the attaching means even when applied to the thinnest silk.

A still further object of the invention is the use of a freely movable button which not only permits of the use of a larger button but also greatly facilitates the operation of attaching and detaching the supporter and hose.

Other objects and advantages of the invention will be apparent from the following description when taken in connection with the accompanying drawing, in which,

Figure 1 is a front elevation of the hose supporter in use.

Figure 2 is a longitudinal section through the supporter and a portion of the hose.

Figure 3 is an enlarged perspective view of the locking button and attaching means therefor.

Figure 4 is a horizontal section showing the hose locked in place, and,

Figure 5 is a sectional view showing a modified form of button.

Referring to the drawing more in detail, the numeral 1 designated the usual adjustable strap attached to the corset and carrying means at its lower end for readily attaching the same to the upper end of the hose indicated by the numeral 2. The member 3, which is composed of two metallic loops 4 and 5 pivoted in the sleeve 6, is secured to the strap 1 by threading the same through the upper loop 4. The lower loop 5 is tapered downwardly for co-operation

with a button 7. This button is made relatively large, as shown in the drawing, for the purpose of providing a greater bearing surface for the material to which it is attached, thereby greatly decreasing the strain put on the material at any particular point. The button shown is of the conventional type having two holes, although a piece of Chinese money or a button having a rearwardly extending shank may be used if desired. In Figure 5 I have shown a button 7' having a cross bar 10 below the surface of the button in order that the attaching means may lie flush therewith.

In order to hold the button 7 in proper relation with respect to the loop 5 and also to allow a free movement of the button in all directions to facilitate attachment to the hose, I have devised the cord 8 which is threaded through the holes of the button and then looped over the sleeve 6. The ends of the cord 8 are secured by means of the windings 9 of threads or the like. By thus securing the ends of the cord the suspension means is materially stiffened, thereby facilitating the manipulation of the button.

In operation, the upper portion of the hose or other garment to be supported is placed over the button and this portion of the garment and the button is inserted into the loop 5, and the garment is thereby securely held. It should be here noted that by means of the flexible connection between the button 7 and loop 5, the button may turn in any direction thereby permitting a much larger button to be used since it may be turned edgewise and passed through the loop 5.

In accordance with the patent statutes I have described what I now believe to be the best embodiment of the invention, but I do not wish to be understood thereby as limiting myself or the scope of the invention, as many changes and modifications may be made without departing from the spirit of the invention, all such I aim to include in the scope of the appended claims.

What I claim as new and desire to secure by Letters Patent is:

1. In a hose supporter, a metallic loop member, a button, a cord threaded through said button, the ends of the cord being

doubled over a portion of the loop member, and thread wound about the overlapped portions of said cord, whereby the latter is materially stiffened.

5 2. A hose supporter comprising a pair of metallic loops, a sleeve in which said loops are pivoted, a button, a cord threaded

through said button, the ends of the cord being doubled over the sleeve, and thread wound about the overlapped portions of said cord, whereby the latter is materially stiffened. ¹⁰

LOUISE F. DION.
